Des. 229,368
Patented Nov. 20, 1973

229,368

FRUIT JUICE EXTRACTOR

Paul Marrié, Dijon, France, assignor to
Etud S.A., Quetigny, France

Filed Dec. 30, 1971, Ser. No. 214,531

Claims priority, application France July 5, 1971

Term of patent 14 years

Int. Cl. D7—04

U.S. Cl. D89—1 A

FIG. 1

FIG. 3

FIG. 2

FIG. 1 is a right-front perspective view of a fruit juice extractor embodying my new design.

FIG. 2 is an elevational view thereof seen from the rear; and FIG. 3 is a top plan view thereof.

The bottom is substantially plain and unornamented, and the side opposite that shown in FIG. 1 is a mirror image thereof.

I claim:

The ornamental design for a fruit juice extractor, as shown and described.
